COILER FOR REVERSING HOT MILLS

Alonzo B. Montgomery, Cincinnati, Ohio

Continuation of application Serial No. 729,604,
 February 19, 1947. This application March 20,
 1953, Serial No. 343,568

8 Claims. (Cl. 263—3)

1

This invention relates generally to metal rolling apparatus. More particularly it relates to a reversing-type hot rolling mill primarily designed for the rapid and efficient rolling of hot steel strips. This application is a continuation of application Serial No. 729,604, filed February 19, 1947, now abandoned.

The preferred form of the invention contemplates a reversing rolling mill construction primarily intended for the rolling of hot strips from a maximum thickness, which is suitable for coiling, down to the final or desired thickness of the sheet or strip. It will be obvious to those skilled in the art that the rolling mill construction hereinafter described may, if desired, be incorporated in a rolling mill table embodying suitable rolls for reducing metal from billet thickness to approximately 2½ inches in thickness which is too thick for coiling. The strip so prepared is then rolled in the reversing mill embodying the invention down to a maximum coiling thickness in a flat condition after which further rolling is accompanied by coiling. During flat rolling, certain of the elements of the coiling rolling mill are moved to a position in which the strip may slide along the rolling table in a flat condition and not be coiled in the coiling furnaces. When the strip is reduced to coiling thickness, the coiling furnaces are used until such time that the thickness of this strip is reduced to the desired dimension, after which the strip is removed from the coiling mill and coiled into suitable form for sale to the trade.

It will be obvious, however, that the shown coiling mill may also be used separate and apart from the billet reducing mill which initially reduces the metal into a plate or sheet of suitable thickness so that it can be rolled in the reversing coiling mill. In such event, the billet is rolled to the desired thickness and then is transferred from the billet rolling table to the coiling mill where it is subsequently rolled to the desired thickness. Also, if desired, the coiling mill may be placed either above or below the billet rolling mill and, after the strip has reached the desired maximum thickness, suitable gates may be closed for transferring the strip from the billet mill to the coiling rolling mill.

A primary object of the present invention consists in the provision of an improved type of coiling furnace which, together with the other features hereinafter described, serves to operate substantially automatically and which is characterized by novel means for picking up and en-

2

gaging the free end of the strip so that the same is projected into the coiler furnace.

Further, the present invention contemplates the provision of a coiler furnace construction in which the means for engaging and anchoring the end of the strip is so constructed and arranged that heat losses normally suffered at the end of the strip are reduced to a minimum and scrap losses are thereby correspondingly reduced.

10 A further object is to provide a hot strip metal rolling mill wherein heat losses due to radiation and convection are maintained at a minimum.

15 A still further object is to provide suitable heating means whereby the heat of the steel strip which is lost during each rolling operation is evenly replenished to the strip each time that it is passed through the reducing rollers.

20 The invention contemplates the provision of a coiler-type furnace in which means are provided for maintaining the coiler drum in predetermined stationary position as the end of the strip enters the furnace together with means automatically operating to commence rotation of the coiler drum when the end of the strip has been properly received and anchored therein.

25 Still another object of the present invention consists in the provision of an improved type of coiler furnace consisting of a refractory base and refractory hood housing the coiler drum and together serving to provide a combustion chamber of such construction and arrangement that heat losses in the said coil strip are reduced to a minimum and that the coil strip on the drum is heated with approximate uniformity around the periphery and end of the coil.

30 Still further, the improved coiler furnace contemplates the provision of a coiler roll mounted for vertical movement within the coiler furnace. This coiler roll is adapted to co-operate with the coiler drum to hold the strip tightly engaged therewith until the coiler drum has made at least one complete revolution and includes substantially automatic means for bringing the coiler roll into engagement with the coiler drum.

35 40 45 Still further, the improved coiler furnace contemplates the use of the coiler roll at the end of a run of the strip through the rolling mill for holding the strip tightly about the coiler drum.

Still further, the invention contemplates the provision of a reversing hot strip mill construction embodying a novel arrangement and operation of guides for guiding the strip to and from the work rolls. In construction of this general type, it has heretofore been conventional to utilize so-called taper guides which have progres-

sively decreasing spacing between them. The present invention, however, contemplates the use of automatically adjustable guides which at all times are maintained substantially parallel.

The improved construction contemplates automatic means for moving the guides on the entering side of the work rolls closer together and the guides on the leaving side further apart thereby assuring precise feeding of the strip through the work rolls. When the strip is fed through the work rolls in the opposite direction, the position of the guides is altered so that the guides on the entering side of the rollers are moved into guiding position and the guides on the exit side of the rollers, which during the preceding operation were inlet guides, are now moved to further open position.

Still further, the invention contemplates the provision for manually positioning the guides in order that the same may be accurately and precisely adjusted for the rolling of strips of various widths, this adjustment being made entirely independent of the automatic control of these guides which operate upon reversal of the mill.

Yet another advantage, object and feature of the present invention resides in the system of substantially automatic control which electrically co-ordinates the various novel and improved features of the mill where the mill can be easily and precisely controlled. These controls are co-ordinated in such a way that the mill, while not being entirely automatic in operation, relieves the operator of many of the detailed controlling functions.

Other objects of this invention will be apparent from the specification and the claims appended thereto.

In the drawings which form a part of this specification and in which the same reference characters are used to designate the same elements in the various figures,

Figure 1 and Figure 2, when placed end to end with Figure 2 at the right end of Figure 1, show in plan view the hot rolling coiling mill with certain of the parts broken away or removed to better illustrate various features of the mill;

Figs. 3 and 4 may be arranged similarly to Figs. 1 and 2 and, when so arranged, illustrate generally in central vertical section the reversible hot strip coiling mill, shown in Figs. 1 and 2;

Fig. 5 shows in end elevation one of the coiling furnaces embodied in the reversing coiling mill;

Fig. 6 is a view taken substantially along the line 6—6 of Fig. 3 looking in the direction of the arrows;

Fig. 7 is a schematic diagram of the electrical network for the driving motors;

Fig. 8 is a schematic diagram of the electrical controlling network for the mill;

Fig. 9 shows diagrammatically the construction of certain of the switches diagrammatically shown in Fig. 8;

Fig. 10 is a schematic diagram of the electrical controlling system for the strip guides;

Fig. 11 is a schematic diagram of the electrical torque-controlling system for the coiler drum motors; and,

Fig. 12 is a section view taken substantially along the line 12—12 of Fig. 1 showing the guide actuating mechanism.

It will be appreciated from a complete understanding of the invention that, in a generic sense, the improvements thereof may be embodied in a wide variety of different rolling mill constructions. Therefore, the embodiment shown in the

drawings is to be taken as illustrative and not as limiting the scope of the invention, which scope is to be limited only by the hereinafter appended claims.

Referring to the drawings by characters of reference, the numeral 1 designates generally a hot strip reversing rolling mill which may be located along a table of a flat-type billet rolling mill having work rolls which receive a metal billet from a furnace. The flat rolling mill may be of any usual type in which the work is passed through the work rolls to reduce the thickness thereof to a suitable dimension for use in the mill 1. After such treatment of the metal, the operator in one of the booths or operating pulpits of the mill 1 actuates suitable controls whereby the strip enters the mill 1.

The mill 1 is brought into operation and the metal strip is fed through the work rolls 14 and backing rolls 15 of the mill 1 in alternate directions until the thickness thereof has been brought down to a coiling dimension. Suitable controls, to be hereinafter described, are then actuated to initiate coiling of the strip about one of the coiler drums 16 or 18 of the right and left coiling furnaces 20 or 22 respectively. The particular furnace 20 or 22 which is first used will depend upon whether the strip is first run through the mill 1 in a right-hand or left-hand direction. After the hot strip has been completely run through the work rolls 14, the coiler drum 16 or 18 upon which the strip is being rolled is stopped and the work is then passed through the work rolls 14 in the opposite direction to be coiled upon the opposite one of the coiler drums 18 or 16. Thereafter, the strip is repeatedly run through the work rolls 14 in alternate directions and coiled upon the drums 16 and 18 alternately until the thickness of the strip has been reduced to the desired thickness. Subsequently, the strip is fed outwardly from the mill 1 to a suitable coiling station (not shown) where it is coiled into suitable form for delivery from the mill.

The reversing coiling mill 1 comprises generally a worktable 24 in which the right and left-hand coiling furnaces 20 and 22 respectively are located. Intermediate between the furnaces 20 and 22 are positioned the work rolls 14 for reducing the thickness of the metal strips fed along the worktable 24 from one of the coiling furnaces 20 and 22 to the other of the coiling furnaces 22 or 20. Any suitable mechanism for controlling the spacing between the work rolls 14 may be used and, since such mechanism is well known to the art, it is not deemed necessary to complicate this disclosure by a detailed showing thereof. The worktable 24 may include one or more rotating rollers 26 over which the metal strip being treated is passed and which rollers 26 may, if desired, be driven by one or more electrically operated motors 28 adjusted to rotate at the speeds of the strip portion supported thereby during rolling operations. If desired, they may be operated similarly to the operation of the motors LCM and RCM to be more fully described hereinafter.

A pair of substantially parallel, spaced guides 30 are arranged adjacent the right-hand side of the work rolls 14 and spaced one on either side of the central axis of the worktable 24. A second set of parallelly arranged, spaced guides 32 are similarly arranged on the table at the left side of the work rolls 14. These guides 30 and 32 are connected by suitable mechanism whereby, when one set of guides, for example, guides 30, are arranged in guiding position, the guides 32

are moved to a further apart position; and, conversely when the guides 32 are arranged in guiding position, the guides 30 are spaced apart a greater distance.

Fig. 12 shows the construction of the adjusting mechanism for the guides 32 having guiding surfaces 130 between which the strip being rolled is guided. A screw-threaded rod 132 is suitably journaled for rotation in bearings, not shown, and has threaded end portions 134 and 136 of opposite hand. Nuts 138 and 140 are threaded on the portions 134 and 136 respectively and are pivotally connected to lever arms 142 and 144 respectively and serve as fulcrum points therefor. The upper ends of the arms 142 and 144 are pivotally connected through link pins 146 to the guides 32. The lower ends of the arms 142 and 144 are pivotally connected through links 148 to diametrically opposite pins 150 of a rotatable member 152 journaled on a shaft 154 suitably held in supports 156. A crank arm 158 is arranged to be moved by a link 160 for rotating the member 152 between the position shown in which the guides 32 are in guiding position to a position in which the lower ends of the arms 142 and 144 are brought inward toward each other and the guides 32 are moved to a retracted or non-guiding position. A similar construction of arms and links actuate the guides 30 and are controlled by a link 162. The reversible guide-adjusting motor GAM is suitably held on a support, not shown, and is connected through suitable reduction gearing 164 for rotating a shaft 166 in opposite directions. The shaft 166 is journaled in suitable bearings 168 and has attached thereto for rotation thereby a pair of crank arms 170 and 172 to which the links 160 and 162 are respectively pivotally attached. The crank arms 170 and 172 are positioned at 180° relative to each other so that as the link 160 is moved toward the table 24 the link 162 will be moved outwardly therefrom. Such movement of link 160 will rotate the rotatable member 152 to the position shown in which the lower ends of the arms 142 and 144 are in their separated position and the guides 32 in their guiding position. Similarly, the outward movement of the link 160 will draw the lower ends of the arms 142 and 144 toward each other and retract or separate the guides 32. The guides 30 are actuated similarly by the link 162 so that the guides 30 will be retracted when guides 32 are in guiding position and vice versa. Suitable switch means GSR and GSL limit the operation of the motor GAM so that the shaft 166 has only limited rotational movement of substantially 180° whereby the arms 170 and 172 are either in the position shown or 180° therefrom.

As will be noted, a hand crank 174 is provided on the rod 132 whereby it may be rotated to adjust the position of the fulcrum nuts 138 and 140 for adjusting the spacing between the guides 32. A similar crank 176 is provided for the corresponding rod for the guides 30 whereby their spacing may be controlled in a similar manner.

The coiling furnaces 20 and 22 are identical and therefore it is believed that a detailed description of one will suffice as a description for both. The furnace 20 comprises a refractory-lined base 34 which is substantially rectangular in cross section and has a closed lower end wall 36 and an open top wall above which a cylindrical, refractory-lined hood 38 is located and which has had a segment of its cylindrical surface removed to provide an opening through its

peripheral surface. The hood 38 and base 34 are suitably heated whereby heat lost during the rolling operations may be returned to the strip. The coiler drum 16 is located within and extends longitudinally of the hood 38. This coiler drum 16 comprises a hollow, cylindrical member 40 having diametrically opposite apertures 42 opening externally into the hollow interior of the member 40. The apertures 42 have one side wall extending at an angle therethrough which is acute with respect to the tangent line of the drum at its intersection with the outer periphery of the drum 16 whereby the leading end of the strip may easily pass therethrough. The inner periphery of the hollow member 40 has a slight protruding portion 43 adjacent the edge of the slots or apertures 42 opposite to the angular side wall, whereby the leading end of the strip being rolled is prevented from passing outwardly through the apertures 42 subsequent to entry into the member 40 and which tends to coil the portion of the strip within the drum 16 should the drum fail to start and come up to speed as soon as the leading strip end enters the same.

The furnace 20 is carried on a suitable supporting base 44, which base also has upwardly extending supports 46 for supporting guide rolls 48 and 50. As shown in Fig. 1, the guide rolls 48 and 50 comprise central shafts 52 upon which are mounted a plurality of spaced disks 54, the upper edge of the periphery whereof lies substantially in the plane of the work surface of the worktable 24. Located intermediate the guide rollers 48 and 50 is a coiler roll 56 which is carried by a vertically reciprocal supporting member 58 operated by a fluid pressure-actuated motor 60 located adjacent the support 44 and movable by the fluid motor into a position in engagement with the outer periphery of the coiler drum 16 and into a lower position in which the peripheral surface of the coiler roll 56 is below the plane of the surface of the worktable 24. Suitably pivoted counterweights 61 aid the movement of the members 58 by the motors 60.

A plurality of guide fingers 62 are carried by the supporting member 58 and are arranged to project between the disks 54 of the guide roll 48. These guide fingers 62 are arranged at such an angle relative to the plane of the worktable 24 that when the coiler roll 56 is engaged with the coiler drum 16, they guide the end of the metal strip being fed into the furnace 20 upward from the plane of the table 24 and through one of the apertures 42 of the coiler drum 16 whereby the end of the metal strip is received within the hollow interior of the member 40. During the time that the end of the metal strip is initially being fed to the coiler drum 16, this drum 16 is held at rest in the position shown in Fig. 4 by suitable control mechanism to be hereinafter described. After the leading end portion of the metal strip being rolled is received within the hollow interior of the member 40, the coiler drum 16 is then rotated whereby the remainder of the strip being fed to the furnace 20 is wound or coiled around the exterior of the member 40. After the member 40 or coiler drum 16 has made at least one complete revolution, the strip will be held to the drum 16 by itself and the fluid motor 60 is de-energized, thereby moving the coiler roll 56 downwardly below the plane of the worktable 24.

The coiler roll 56 is held in this position until such time that the strip is either through the work rolls 14 or is about to go through them, at

which time the fluid motor 60 is again energized, bringing the coiler roll 56 into contact with the portion of the strip rolled about the coiler drum 16 whereby the strip is held tightly to the drum 16 and against unwinding. It is to be understood that the coiler drum 16 will be automatically stopped after the strip has passed completely through the work rolls 14. In this condition, as explained hereinbefore, the strip is ready to be passed in the reverse direction to the work rolls 14 and recoiled upon the coiler drum 18 of the left-hand coiling furnace 22. Suitable electric motors LCM and RCM drive the guide rolls 48 and 50 and the coiler roll 56 of the left and right furnaces 22 and 20, respectively, through suitable gearing 66 and shafts 68, 70 and 72.

Suitable mechanism to be hereinafter described controls operation of the motors LCM and RCM at the proper speed so that there is little, if any, difference in speed between the speed of the strip and the peripheral speed of the rolls 48, 50 and 56.

The coiler drums 16 and 18 are driven by motors RRM and LRM, respectively, through a suitable gearing 76 and shafts 78. The motors LRM and RRM, like the motors LCM and RCM, are controlled by mechanism to be hereinafter described, so that the coiler drums 16 and 18 are rotated at approximately the correct speed to wind the strip about their periphery at a speed such that the amount of metal being rolled on the drum is equivalent to the speed at which the metal strip is fed thereto.

It is believed that the remainder of the details of construction may best be described in connection with the description of operation of the rolling mill. Assuming that it is desired to condition the coiling mill for operation, the line switches LS1 and LS2 are closed thereby energizing the lines L1 and L2. The billet which has been removed from the furnaces and run through the initial work rolls where it has been reduced from the original approximate 4" thickness to substantially 40% of that thickness, or slightly less than 2½" in thickness, enters one of the furnaces 20 or 22 depending upon whether the rough work rolls are at the right or left-hand side of the hot-strip reversing mill 1. In this instance, it is assumed that the rough work rolls are arranged to the right of the right-hand coiler furnace 20 and the leading end of the strip enters through the furnace 20 to the work rolls 14 associated with the worktable 24.

The next operation is to pass the strip in flat condition back and forth through the work rolls 14 until such time that the thickness thereof has been reduced to a thickness in which the strip may be easily coiled in the coiling furnaces 20 and 22. It will be assumed that the operation in the left booth or pulpit is controlling the rolling of the flat sheet down to a thickness in which it may be coiled in the furnaces 20 or 22. If desired, the strip may be rolled down to coiling thickness in other work rolls separate and apart from the mill 1.

The left operator moves his master switch LMS in a direction to close the contacts LMS1-1 and 2 thereof. The strip will be engaging the right flag switch RF and holding it in a position to maintain the contacts 1, 2 and 3 thereof closed. It is further assumed for this operation that the left and right trigger switches LT and RT are in their lower position maintaining their contacts 1 in open-circuit position and their contacts 2, 3, and 4 in closed-circuit position. Closure of the contacts LMS1-1 of the left master

switch LMS energizes a circuit from the line L1 through the contacts LMS1-1, the contacts LT2, the energizing coil of the relay CL, the contacts CR10 of the relay CR, and the contacts E2 of the emergency stop relay E, to the line L2. Closure of the contacts LMS1-2 is without effect since the switches LLM and RLM and the contacts RSL2 of the relay RSL are in open-circuit position.

10 Energization of the relay CL closes the contacts 2, 3, 4, 5, 6, 7, 10, 11 and 12 thereof, opens the contacts 1, 8, 8a and 9 thereof and decreases the magnitude of the resistance FR1 which is located in the circuit of the main generator field MGf. The effect of the opening of the contacts CL8 and CL8a will be described hereinafter.

15 The construction of the relays CL, CR, RSL and RSR is quite similar and somewhat unique. Generally, they comprise a movable element or rod 90 having an armature 92 which is moved under the influence of a solenoid winding 94. The rod 90 is moved toward down or de-energized position by suitable means such as a spring 96 and toward up or energized position by the magnetic effect exerted on the armature 92 by the winding or coil 94. A dash pot 98 permits rapid movement of the rod 90 to deenergized position but provides a controlled gradual movement toward energized position. A contact closing element 100 is associated with each set of normally closed relay contacts and is in fixed position relative to the rod 90 so that upon initial movement of the rod 90 toward energized position the normally closed contacts are opened. A relatively movable contact-closing element 102 is associated with each set of normally open contacts. The elements 102 are loosely carried by the rod and are each engaged by one end of a spring 104 and urged thereby into engagement with abutments 106 on the rod 90. The abutments 106 are so spaced on the rod 90 relative to its de-energized position and the position of the set of normally open contacts with which it is associated, that it is held by the abutment out of circuit-closing contact therewith. The other ends of the springs 104 engage abutments 108 on the rod 90. Upon energization of the coil 94, the rod 90 moves upwardly and the elements 102 make an electrical circuit between the contacts with which they are associated and, as the dash pot 98 permits further upward movement of the rod 90, the springs 104 compress and permit such further movement.

20 The relays CL—CR and RSL—RSR are arranged in pairs. The rods 90 of the relays each have a projecting finger 110 which engages a pin or abutment 112 of a spur gear 114 meshing with a rack 116. The fingers 110 or relays CL and CR project toward each other and are each engageable with the pin 112 of the single gear 114 associated therewith. Likewise, the fingers 110 or the relays RSL and RSR are each engageable with pin 112 of the single gear 114 associated therewith. As the rod 90 of relay CR or CL moves upward, the associated gear 114 is rotated moving the associated rack 116 upwardly causing a contact element 118 carried thereby to move along the resistance FR1 to decrease the portion thereof included in circuit with winding MGf. A spring 120 acts to return the rack 116 associated with the relays CL or CR upon deenergization of the relays. It is to be understood that either relay acting alone can move the associated rack 116 upwardly so that energization of one controls the position of reduced

resistance of FR1. If desired, the elements 100 could be constructed similarly to the elements 102 and the abutments thereof corresponding to 106, as well as the shown abutments 106, could be arranged to provide any sequence of opening and closing of the contacts associated with the relay. The relays RSL and RSR are similarly paired and control the effective value of the resistance FR2 for controlling the current flowing through the field MMf. In this instance, however, as the relay RSL or RSR moves upward, the value of the resistance FR2 included in the circuit of the field MMf is increased to progressively increase the speed of the main motor MM.

Opening of contacts CL1 opens the dynamic braking circuit through the resistor DR1. Closure of contacts CL2 connects the armature circuits of the main generator MG and the main motor MM; the motor MM being connected for driving the rolls 14. Preferably the contacts CL1 open just before the contacts CL2 close. Closure of contacts CL3 and CL4 closes a circuit from the line L1 through contacts CL4, the main generator field MGf, the contacts CL2 and armature resistor FR1 to the line L2. The main motor field MMf was energized upon closure of the switches LS1 and LS2 since it is directly connected between the lines L1 and L2 through the resistor FR2. The main motor MM so connected will now rotate the rolls 14 in a direction to roll the strip in a direction from right to left. Closure of the contacts CL5 completes a circuit from the line L1 through the contacts CL5, the resistor FR3 and the left and right generator compensating field windings LGef and RGef; the purpose of which will be set forth herein-after.

Closure of contacts CL6 and CL7 closes the armature circuit of the guide adjusting motor GAM, whereby the right-hand guides 30 will be brought to guiding width for the strip which is being rolled. The left-hand guides 32 at the same time will be moved apart out of guiding relationship to the sheet. Upon movement of the guides 30 into guiding position, the limit contacts GSL will open to de-energize the motor GAM.

Closure of the contacts CL10 is with no effect. Closure of the contacts CL11 energizes circuits from the line L1, through contacts CL11, through the coil of the relay LSC, through the parallelly arranged switch LRLS and contacts 4 of the left trigger switch LT to the line L2, and through the coil of the relay RSC, the parallelly arranged switch RRLS and contacts 4 of the right trigger switch RT.

Opening of the contact CL9 prevents the closure of the circuit through the control coil of the relay CR and is merely an interlocking arrangement whereby the relay CR may not be operated when the relay CL is energized.

Subsequent to opening and closing of the contacts of the relay CL, the rod 90 thereof moves upward under control of its dash pot 98 compressing its associated spring 104 reducing the portion of the resistance FR1 included in the circuit of the main generator field MGf, whereby the strength of this field is increased and the potential output of the main generator MG is increased thereby increasing the speed of the main motor MM.

The energization of the CL relay, among other functions, therefore acts to energize the main motor MM in a left-hand rolling direction to bring it up to a first or threading speed, and to

adjust the guides 30 and 32 for guiding the strip in its left-hand travel through the rolls 14. Hereinafter, these functions of the relay CL will be referred to as energizing the motor MM and adjusting the guides for left-hand rolling.

Energization of the relay LSC opens the contacts 1 and 2 thereof and closes the contacts 3, 4 and 5 thereof. Opening of the contacts 10 LSC1 and LSC2 opens respectively the dynamic braking circuits for the motors LCM and LRM. Closing of the contacts LSC3 and LSC4, which preferably occurs slightly after opening of the contacts LSC1 and LSC2, connects the armatures of the motors LCM and LRM to the generator LG. Closure of the contacts LSC5 connects the main field LGmf of the generator LG across the armature circuit of the constantly excited pilot exciter PE, which is driven by the main motor MM and will, therefore, generate a potential which is proportional to the rotational speed of the main motor MM.

Energization of the relay RSC opens the contacts 1 and 2 thereof and closes the contacts 3, 4 and 5 thereof. Preferably, the opening of the contacts 1 and 2 thereof occurs slightly before the closure of the contacts 3, 4 and 5 thereof. Opening of the contacts RSC1 and RSC2 opens, respectively, the dynamic braking circuits of the 20 motors RCM and RRM. Closure of the contacts RSC3 and RSC4 connects the armature circuits of the motors RCM and RRM, respectively, to the generator RG. Closure of the contacts RSC5 connects the main field RGmf of the generator 35 RG to the output of the pilot exciter PE.

The relays LSC and RSC, therefore, act upon energization to connect the armatures and fields of the motors LCM—LRM and RCM—RRM to the generator LG and RG, respectively, and to 40 de-energize the dynamic braking circuits of these motors, whereby they drive the coiler drums 16 and 18, guide rolls 48 and 50 and coiler rolls 56 in the proper direction determined by the relative polarization of the armatures and fields thereof. The constantly excited pilot exciter PE, it is noted, is directly rotated by the main motor MM and is driven in the same direction. Therefore, when the main motor MM is rotated in a direction to rotate the work rolls 14 for rolling 50 in a left-hand direction, the potential generated by the exciter PE will be of one polarity and upon the reverse rotation of motor MM the potential will be of a reverse polarity. The main fields LGmf and RGmf of the left and right generators 55 LG and RG will be supplied with a potential of a polarity which is dependent upon the direction of rotation of the main motor MM. Since the fields LCMf—LRMf and RCMf—RRMf of the motors driven by the generators LG and RG, respectively, are of a fixed polarity as determined by the polarity of the line L1 and L2, the motors LCM—LRM and RCM—RRM will rotate in directions as determined by the master motor MM.

The field and armature polarities of the motors LCM, LRM, RCM and RRM are initially adjusted to provide for motor rotations so that the coiler drums 18 and 16, the coiler rolls 56 and rolls 48 and 50 are rotating in the proper directions for transfer of the strip from right to left or left to right as determined by the rotation of the main work rolls 14. In the remainder of the description, therefore, the relays LSC and RSC will be described merely as energizing the motors LCM—LRM and RCM—RRM of the left and 65 right coiling stands or furnaces 22 and 20, re-

spectively, for transfer of the strip being rolled.

It will now be seen that all of the motors MM, LCM, LRM, RCM and RRM are now rotating under control of the generators LG, MG and RG and the pilot exciter PE. The field and armature connections of the above-identified motors are all respectively connected so that they turn in the proper direction for moving the strip to be rolled in the left-hand direction through the work rolls 14. The rolling of the strip through the rolls 14 may continue at this motor speed for a reason which, as will be apparent further in description of the operation, is known as threading speed or, if desired, the speed may be increased to rolling speed. If rolling speed is desired, the switch LLM is closed to complete a circuit from the line L1 through contacts LMS1-2, the switch LLM, contacts RF2, the energizing coil of the relay RSL, contacts E4 to the line L2. Energization of the relay RSL closes the contacts 1 and 2 thereof and decreases the current flow through the main motor field MMf. Closure of the contacts RSL2 completes a holding or locking circuit for the relay RSL and subsequent opening of the switch LLM, therefore, does not interrupt the high speed rolling operation. Upon actuation of the relay RSL, the contacts 1 thereof close rapidly but, because of the dash pot control of the arm of the resistance FR2, the decrease of field strength of the motor MM will occur gradually so that the acceleration of the motor MM will be gradual producing an effect similar to that produced upon actuation of the relays CL or CR. After the expiration of the predetermined time as determined by the dash pot 98 thereof, the full resistance of the resistor FR2 is included in the field circuit MMf, whereby the speed of the main motor MM is increased sufficiently to produce rolling speed of the strip. Preferably the abutment 106 controlling the element 102 associated with the contacts RSL2 is positioned to close at substantially the time the rod 90 of the relay RSL reaches its upper limit and upon de-energization of the relay to open almost immediately so that upon increase in speed the operator maintains the switch LLM depressed for the period of dash pot operation during which time the holding contacts RSL2 are closed.

This increase in speed of the main motor MM drives the pilot exciter PE at an increased rate, thereby increasing the excitation on the main field coils LGmf and RGmf of the generators LG and RG, respectively, and an increased potential will be generated thereby. An increase in the potential applied to the motors LCM, LRM, RCM and RRM will cause their speed to increase and the rolling operation will proceed at rolling speed, for example, 1000 feet per minute.

As the end of the strip being rolled approaches the rolls 14, the operator moves the switch LMS to neutral position. This opens contacts LMS1-2 which de-energizes the winding of the RSL relay opening the contacts 1 and 2 thereof. As stated above, the contacts RSL open almost immediately so that a subsequent reclosure of the switch LMS in left position for closing contacts LMS1-1 and LMS1-2 will not re-energize the relay RSL but will provide merely operation at threading or low speed.

When the strip has moved through the work rolls 14, the operator in the left pulpit moves master switch LMS to the neutral position opening the contacts LMS1-1 and LMS1-2. Opening of the contacts LMS1-1 de-energizes the coil of

the relay CL which de-energizes and brakes the motor MM but which is without effect on the motor GAM; it having already been de-energized by opening of the limit contacts GSL. Opening of the contacts CL2, 3 and 4 disconnects the main motor, armature and field, MM and MGf, respectively, from the main generator MG. Closure of the contacts CL1 energizes the dynamic braking circuit for the main motor MM through the dynamic braking resistor DR1. Opening of the contacts CL5 de-energizes the circuit from the line L1 through the generator field LGcf and RGcf. Opening of the contacts CL6 and CL7 is without effect since the circuit therethrough has previously been de-energized by the guide switch GSL. Closure of the contacts CL9 is without effect since both master switches LMS and RMS are now in their neutral position and the right trigger switch RT is also in its down position, as shown. Closure of the contacts CL10 is also without effect since the left trigger switch LT is in its down position, as shown. Opening of the contacts CL-11 de-energizes the relays LSC and RSC; the contacts CR11 being in open circuit position.

De-energization of the relays LSC and RSC de-energizes and brakes the motors LCM, LRM, RCM and RRM. Opening of the contacts 3, 4 and 5 of the relays LSC and RSC disconnects the armature circuits of the motors LCM and LRM and the armature circuits of the motors RCM and RRM, respectively, from the generators LG and RG, respectively. Closure of the contacts 1 and 2 of the relays LSC and RSC closes the dynamic braking circuits through the resistors DR2, DR3, DR4 and DR5, respectively, whereby the motors LCM, LRM, RCM and RRM are brought to rest.

It is now assumed that the strip is still of a thickness which is too great to be coiled in the coiling furnace 22 and that another pass of the strip is to be made through the work rolls 14 without coiling. The movement of the strip to the right may be controlled by the operator in either of the left or right pulpits. For convenience, it will be assumed that the operator in the left pulpit is still controlling the rolling operation. The left master switch LMS is moved in a direction to close the contacts LMS1 and LMSr2. Closure of the contacts LMS1 closes a circuit from the line L1, through the contacts LMSr1, through the contacts 1 of the now closed left flag switch LF, through the now closed contacts CL9, through the energizing coil of the relay CR, through the now closed contacts E1 of the emergency switch E to the line L2. Closure of the contacts LMSr2 is without effect since the switches RRMS and LRMS are presently in open circuit position and the contacts RSR3 are also in open circuit condition.

Energization of the relay CR closes the contacts 2, 3, 4, 5, 6, 7, 9, 11 and 12 thereof and opens the contacts 1, 8, 8a and 10 thereof. The effect of the opening of contacts CR8 and CR8a will be described hereinafter. Preferably the contacts CR1 are opened just a little ahead of closure of the contacts CR2. Opening of the contacts CR1 de-energizes the dynamic braking circuit of the main motor MM through resistor DR1 and closure of the contacts CR2 connects the armature circuit of the main motor MM to the output of the main generator MG. Closure of the contacts CR3 and CR4 connects the main generator field MGf between the lines L1 and L2, through the resistor FR1. The arm or finger 110 under control

of the dash pot 98 will move upwardly to gradually cut out the resistance in this circuit due to the resistor FR1; thereby bringing the main motor MM up to speed. Closure of the contacts CR5 completes an energizing circuit for the generator compensating field LGcf, through the resistor FR3. Closure of the contacts CR6 and CR7 completes a circuit through the gage adjusting motor GAM whereby the guides 32 will be brought together into proper guiding position and the guides 30 will be moved apart. A guide limit switch GSR will open the circuit of the guide adjusting motor GAM upon bringing of the guides 32 to their proper guiding position.

Energization of the relay CR, therefore, performs for a part of its function the energization of the motors MM and GAM. It will be noted that the polarity of the potential supplied by the generator is the opposite to that supplied upon the energization of the relay CL since the potential across the generator field MGf is reversed to that due to energization of the CL relay. Since the potential supplied to the motor field MMf is of constant polarity, the reversal of the potential supplied to the armature of the motor MM will cause the main motor to rotate in a direction opposite to that due to energization of the relay CL, whereby the strip will be rolled from left to right.

Closure of the contacts CR9 is without effect since the contacts 1 of the right trigger switch RT are now in open-circuit position. Opening of the contacts CR10 is also without effect except to prevent undesired energization of the relay CL. Closure of the contacts CR11 completes a circuit from the line L1 through the contacts CR11, through the energizing coil for the relays LSC and RSC. The remainder of the circuit from the coil of the relay LSC is completed through the now closed contacts 4 of the left trigger switch LT to the line L2; while the remainder of the circuit for the energizing coil of the relay RSC is completed through the now closed contacts 4 of the right trigger switch RT to the line L2.

Energization of the relays LSC and RSC energizes, respectively, the motors LCM—LRM and RCM—RRM as described above. A reversal in direction of the rotation of the main motor MM and, consequently, the pilot exciter PE which is driven thereby, since the field of the pilot exciter is maintained energized at one polarity, will result in a reversal in potential of the output thereof. Therefore, closure of the contacts LSC5 and RSC5 will cause an excitation of the main field LGmf and RGmf of the generators LG and RG, respectively, opposite to that which occurred when the relays LSC and RSC were actuated by the relay CL. Since the direction of rotation of the generators LG and RG is maintained the same, the potential output of the generators LG and RG will be of opposite polarity to that when the main motor MM was rotating in a direction to move the work strip from right to left. The main fields of the motors LCM, LRM, RCM and RRM are energized with a constant polarity potential by the lines L1 and L2 and, therefore, the direction of rotation of the motors LCM, LRM, RCM and RRM will be opposite to that which occurred when the strip was being rolled through the work rolls 14 in a direction from right to left or in a direction for moving the strip from left to right. High speed rolling is accomplished by closing one of the switches LRMS or RRMS with the same effect on the main motor as occurred above when 75

the strip was moving to the left and switch LLM was closed.

After the strip has moved in a right-hand direction through the work rolls 14, the operator again moves his master switch LMS to the neutral position opening the contacts LMSr1 and LMSr2 thereof to de-energize the relay RSR and then recloses to continue at threading speed. To stop the rolling, the switch LMS is again moved to neutral position to open the contacts LMSr1 and LMSr2. Opening of the contacts LMSr1 deenergizes the control relay CR since the contacts 1 of the right trigger switch RT and the contacts RMSr1 and the contacts RSR2 are all in open condition. Opening of the contacts LMSr2 is without effect since the relay RSR is already de-energized.

De-energization of the relay CR acts to close the dynamic braking contacts 1 thereof and open the potential supplying contacts 2, 3, 4 and 5 thereof for dynamically braking the main motor MM and de-energizing the circuits for the main generator field MGf and the compensating fields LGcf and RGcf of the generators LG and RG. Since the circuit for the motor GAM was previously de-energized by the limit switch GSR, the opening of the contacts CR6 and CR7 is without effect.

Opening of the contacts CR9 is without effect. Closure of contacts CR10 is without effect. Opening of contacts CR11, however, de-energizes the energizing circuits for the relays LSC and RSC to connect the dynamic braking circuits of the motors LCM, LRM, RCM and RRM and to disconnect these motors from their respective generators RG and LG. The strip is manually rolled back and forth substantially as hereinbefore described under control of the operator in either the left or right pulpit until such time that the thickness thereof has been reduced sufficiently so that it will coil readily in the coiling furnaces 20 and 22.

Assuming that the strip has reached this thickness and it is located in a position in which it extends through the right-hand furnace 20 and will be rolled through the work rolls 14 in a left-hand direction under control of the operator in the left pulpit, the operator raises the left trigger switch LT thereby closing the contacts 1, 5 and 6 thereof and opening the contacts 2, 3 and 4 thereof. Closure of the contacts LT1 prepares a circuit through the contacts CL10 which are now open. Closure of contacts LT5 prepares a circuit through the left flag switch LF, the contacts LF3 thereof now being open because the strip is on the right-hand side of the work rolls 14 and not in a position to move this switch to its actuated position. Closure of the contacts LT6 energizes a circuit from the line L1, through the energizing winding of the fluid supply valve VL, through the contacts LT6 and the normally closed contacts TL2 and TR2 to the line L2. This last-described circuit causes fluid to be admitted to the hydraulic cylinders 60 to raise the coiler roll 56 of the furnace 22 into engagement with the peripheral surface of the coiler drum 18. Opening of the contacts LT2 is without effect. Opening of the contacts LT3 opens the shunt circuit around the contacts RF2 and the contacts RSL2; switches LLM and RLM now being in open-circuit position. Opening of the contacts LT4 opens the shunt circuit around the contacts TL1 and switch LRLS. The change in circuit conditions with the exception of the actuation of the valve VL is preparatory only.

The operator now moves the left master switch LMS to close the contacts LMS1-1 and LMS1-2. Closure of the contacts LMS1-2 is without effect, while closure of the contacts LMS1-1 completes a circuit from the line L1, through the contacts LMS1-1, contacts RF1, the energizing coil of the relay CL, contacts CR10 and E2 to the line L2. Energization of the relay CL starts the main motor MM and pilot exciter PE and adjusts the guides 30 and 32 as described above in connection with flat rolling.

Closure of the contacts CL10 closes a circuit from the line L1, through the contacts LT1, the contacts CL10, the contacts RF1-1, CR10, E2, to the line L2 by-passing the contacts LMS1-1. The energization of relay CL and, consequently, the motor MM is now under control of the right flag switch RF. Closure of the contacts CL11 energizes the energizing windings of the relays LSC and RSC and, as hereinbefore described, this starts the motors LCM, LRM, RCM and RRM in the correct rotational directions. The left-hand motor LRM will rotate the coiler drum 18 until one of the apertures 42 thereof is positioned substantially as shown in the drawing (see Fig. 3) so that when the strip is fed into the furnace 22, it will go through this aperture and into the interior of the hollow cylindrical member 40 of the drum 18. When the drum 18 has reached this position, the limit switch LRLS thereof will open. Since contacts LT4 and TL1 are open, the relay LSC will be de-energized and brake the motors LRM and LCM, as above described. The limit switch LRLS is selective as to direction in its operation and opens only upon clockwise rotation of the drum 18.

The strip is now proceeding from right to left through the work rolls 14. When the leading end thereof engages the left flag switch LF, it will close the contacts 1, 2 and 3 thereof. Closure of the contacts 1 and 2 has no effect but closure of contacts LF3 completes a circuit from the line L1, through the contacts LT5, LF3, CL12, through the energizing coil of the relay TL to the line L2. Energization of the relay TL, after a predetermined time interval which is sufficient for the end of the strip to enter the aperture 42 of the drum 18, closes its contacts 1 and opens its contacts 2. Closure of the contacts TL1 completes a by-pass circuit around the switch LSLR and completes a circuit from the line L1 through the contacts CL11, the energizing coil of the relay LSC and through the contacts TL1 to the line L2. Energization of the relay LSC will act immediately to start the motors LCM and LRM to coil the strip.

Opening of the contacts TL2 de-energizes the energizing circuit for the valve VL and which valve, after a predetermined time interval determined by the discharge of the condenser C1 connected in shunt with the coil of valve VL, will close and allow the fluid to escape from the ram 60 and the left coiler roll 56 to move out of the path of the strip. The timing of the discharge of the condenser C1 is adjusted to close the valve VL after the coiler drum 18 has made just over one complete revolution so that the strip has locked itself securely to the drum 18.

The strip is now rolling through the work rollers 14 and into the furnace 22 at a relatively slow or threading speed, for example, 400 feet per minute. If the work was rolled at this speed, the furnace would be uneconomical in operation since the usual length of a strip of rolling thickness is several hundred feet. Therefore, after

the drum 18 has been threaded or has had the end of the strip attached thereto, it is usually desirable to operate the remainder of this rolling operation at a much higher speed.

To speed up the mill to rolling speed, the operator closes the switch LLM which energizes the relay RSL to speed up the motors MM, LCM, LRM, RCM and RRM as described in connection with flat rolling. With the mill 1 running at rolling speed and under coiling conditions, the right trigger switch RT is moved to its up position closing contacts 1, 5 and 6 thereof and opening contacts 2, 3 and 4 thereof. The effect is preparatory only.

Preferably, the operator controlling the rolling watches the end of the strip being rolled and when it is approaching the furnace 22, the left master switch LMS is moved into neutral position opening the contacts LMS1-1 and LMS1-2 thereof placing the motors at threading speed and under control of the right flag switch RF. Opening of the contacts LMS1-2 de-energizes a circuit through the energizing coil of the relay RSL whereby the contacts 1 and 2 thereof are opened. In this instance unlike the flat rolling, opening of the contacts RSL1 is without immediate effect since the contacts RF1 of the right flag switch are now closed in by-pass arrangement around the contacts RSL1 but does put the relay CL under control of the right flag switch RF. Opening of the contacts RSL3 de-energizes an obvious holding circuit for the coil of the relay RSL. De-energization of the relay also causes the resistance of R2 to increase the current flowing in the field circuit MMf of the main motor MM to increase the field excitation of the main motor MM, decreasing its speed and also the speed of the pilot exciter and, consequently, that of the motors LCM, LRM, RCM and RRM to the initial or threading speed of the mill 1 which proceeds with the master switches LMS and RMS in neutral position under control of the right flag switch RF.

As the end of the strip being rolled passes the right flag switch RF, this switch moves to its open condition opening its contacts 1, 2 and 3. Opening of the contacts 2 thereof is without effect. Opening of contacts RF1 de-energizes the energizing coil of the relay CL braking the main motor MM and opening control contacts 10, 11 and 12 thereof and closing the control contacts 9 thereof. Closure of the contacts CL9 is without effect since it is merely a safety switch to prevent operation of the relay CR when the relay CL is operated. Opening of the contacts CL11 de-energizes the relays LSC and RSC to brake the motors LCM, LRM, RCM and RRM. Opening of the contacts CL12 de-energizes the relay TL closing the contacts TL2 which, if the trigger switches LT and RT are in their up position with the contacts 5 thereof closed, will energize the valves VL and VR through obvious circuits to move the coiler roll 56 into engagement with the coiler drum 16 and the strip wound about the coiler drum 18. It is realized that there will be a certain amount of inertia in the coiler drum 18, which by this time will have substantially all of the steel strip spirally wound therearound, and preferably the operation of the switches and the effect of the dynamic braking circuit itself is such that the coiler drum 18 will come to rest with the end of the strip spaced toward the work rolls 14 from the left flag switch LF, so that this switch will be maintained in a position to keep

the contacts LF1 and LF2 in closed-circuit position.

If, however, the operator does not move the master switch LMS to the neutral position above described, no great damage will result other than perhaps the end of the strip will roll too far along the table and may move beyond the left flag switch LF. Under these conditions, the left master switch LMS will be in a position in which the contacts LMS1-1 and LMS1-2 are closed. As the end of the strip passes the right flag switch, the contacts 1, 2 and 3 thereof open. Opening of the contacts RF1 has no effect since under these conditions the contacts RSL1 will be closed. Opening of the contacts RF2 de-energizes a circuit through the contacts RSL2 which de-energizes the energizing coil of the relay RSL. Opening of the contacts RF3 has no effect since the contacts CR12 are open. De-energization of the relay RSL acts to increase the current flow through the main motor field MM_f due to the reduction of the resistance FR2.

The contacts RSL 1 and 2 open upon de-energization of relay RSL. Opening of the contacts RSL1 opens the circuit through the energizing winding of the relay CL since contacts RF1 and LT2 are now open. Opening of the contacts RSL2 is of no effect since RSL already has been de-energized. De-energization of the relay CL acts as hereinbefore stated to brake the main motor MM and energize the valves VL and VR as above described. If the strip moves too far to the left and passes the left flag switch LF, the manual inching control MIR may be actuated to close the relay CR to initiate operation of the main motor MM and to energize upon closure of the contacts CL11 to energize the relay LSC to initiate operation of the motors LCM and LRM to bring the strip past the left flag switch LF. The strip now being substantially coiled around the coiler drum 18 with its end extending beyond the flag switch LF toward the work rolls 14, the operator moves the left master switch LMS into a position which closes the contacts LMS1 and LMS2. Closure of the contacts LMS2 is without effect since switches LRMS and RRMS are open and also contacts RSR3 are open. Closure of contacts LMS1 completes a circuit from the line L1 through the contacts LMS1, LF1, CL9, and the energizing coil of the relay CR, through the contacts E1 to the line L2. Energization of the relay CR initiates the operation of the main motor MM and the setting of the guides for guiding the strip in left to right movement through the rolls 14. Energization of the relay CL also energizes the coils of the relays LSC and RSC for operation of the motors LCM, LRM, RCM and RRM, as hereinbefore described. In this case, however, as soon as the motor RRM has rotated the coiler drum 16 so that one of its apertures 42 thereof is substantially in the position shown in Fig. 4 for receiving the end of the strip, the limit switch RRLS thereof will open for de-energizing the relay RSC, whereby the motors RCM and RRM will be disconnected from the generator RG and their dynamic braking circuits will be applied. Limit switch RRLS like limit switch LRLS is directional in its operation; the switch RRLS opening only when drum 16 is rotating counterclockwise.

The motors LCM and LRM will be rotating and the strip will be fed through the work rollers from left to right toward the furnace 29. When the leading edge of the strip engages the right flag switch RF, the contacts 1, 2 and 3 thereof will

close. Closure of contacts RF1 and RF2 is without effect, while closure of the contacts RF3 completes a circuit from the line L1, through contacts RT5, RF3, CR12, the coil of the relay TR to the line L2. Energization of the relay TR causes its contacts 1 to close and its contacts 2 to open. Closure of the contacts TR1 completes an energizing circuit from the line L1, through the contacts CR11, the coil of the relay RSC, contacts TR1 to the line L2 at the expiration of a pre-determined time interval because of the dash pot associated therewith, to initiate operation of the relays LSC and RSC subsequent to entering of the strip end into the drum 16. Opening of the contacts TR2 acts to de-energize the valves VL and VR. The condensers VLC and VRC are charged upon energization of the coils of the valves VL and VR and upon opening of the energizing circuits of these valves discharge through the respective coils to maintain the coils energized for a short time period subsequent to operation of the motors RCM and RRM so that the right and left coiler rolls 56 will not be withdrawn downwardly until the drum 16 has made one complete revolution.

The strip is now being fed from left to right through the mill 1 at threading speed. To increase this speed to rolling speed, the operator closes the switch LRMS completing a circuit from the line L1, through the contact LMS1, switch LRMS, contacts LF2, coil of the relay RSR, contacts E3, to the line L2. Energization of the relay RSR causes the contacts 1 and 2 thereof to be closed and the resistance FR2 gradually to be placed in the field circuit MM_f, thereby weakening the field of the motor MM and increasing its speed. Closure of the contacts RSR1 and RSR2 has no effect other than to provide holding circuits.

The operator watches the number of turns of the steel strip remaining upon the coiler drum 18 and when this is reduced to one or two turns, he moves his left master switch LMS to the neutral position opening the contacts LMS1 and LMS2. Opening of the contacts LMS1 is without effect since it is by-passed by the closed contacts RT1 and CR9. Opening of the contacts LMS2 opens the energizing circuit for the relay RSR which immediately opens, opening the contacts 1 and 2 thereof and causing the resistance FR2 to be moved from the field circuit MM_f to reduce the speed of rolling to threading speed. When the end of the strip has passed by the left flag switch LF, the contacts 1, 2 and 3 thereof will open. Opening of the contacts LF1 de-energizes the relay CR to brake the motor MM and de-energize the relays LSC and RSC for braking the motors LCM, LRM, RCM and RRM. Opening of the contacts LF3 de-energizes the winding of the relay TL closing the contacts TL2 for energizing the valves VL and VR and the condensers VLC and VRC. Further reduction of the thickness of the strip and alternate winding and unwinding of the strip between the two coiler drums 16 and 18 continues in the manner described until such time as the thickness of the strip has been reduced to the desired dimension. After the strip is reduced to the desired dimension, it will be wound about one of the drums 16 or 18. Assuming that it is wound on the coiler 16, the left and right trigger switches are returned to the position shown in Fig. 8, the work rolls 14 are spaced apart by a suitable means well known in the art and, therefore, not shown or further described in this application, and the left master

switch LMS is moved so that the contacts LMS1-1 and LMS1-2 are closed. The strip now runs down along the table 24 through the now spaced apart work rolls 14 through the furnace 22 and along the worktable where it is coiled by suitable mechanism well known in the art and not further described, after which it is removed for further heat treating or delivery to the customer.

While the description of the operation has been specific with respect to the circuit control afforded by the left master switch LMS, it will be obvious that the right master switch RMS is connected in parallel relationship with the left master switch and that operators in either of the left or right pulpits may take control of the work. A duplicate set of left and right trigger switches may be provided; however, in usual installations one set is sufficient; the operator having this set initially starting the coiling operation. The switches RRMS and RLM are switches appearing in the right pulpit and correspond to the switches LLM and LRMS in the left pulpit. Switches MIL and MIR are, respectively, inching controls for moving the strip along the table manually without resort to any automatic control system for placing the motors in automatic operation.

It will be noted from the above description of operation that preferably the relays RSL and RSR act to promptly close their contacts 1 but the closure of their contacts 2 is delayed until substantially all of the resistance FR2 has been put into the energizing circuit for the main motor field MMf. In increasing the speed of the motor MM, it is necessary therefore for the operator to keep the switches LRMS, RRMS, LLM or RLM manually closed until the expiration of the time interval necessary to close the holding contacts 2 of the relay RSL or RSR. Such contacts 2 could be adjusted to close promptly and a momentary closure of the switches LRMS, RRMS, LLM or RLM would be sufficient. In this event, however, it would be necessary for the operator to maintain the master switch LMS or RMS in neutral position a sufficient time to permit opening of the contacts 2 of relay RSL or RSR. The contacts 1 of the relays RSL and RSR should remain closed to maintain the relay CL or CR energized until such time as the resistance FR2 has been reduced to minimum value for low speed motor field operation.

The relay E is operated by closure of switch ES which energizes its control winding through an obvious circuit for emergency stopping of the rolling operation. Upon such energization, the relays CR, CL, RSL and RSR are immediately de-energized for braking the motors MM, LCM, LRM, RCM and RRM.

Compensating field windings LGcf and RGcf have been provided for the generators LG and RG, respectively, and are under control of the contacts CL5 and CR5. Their field windings are energized with a fixed polarity potential between the lines L1 and L2. It will be obvious therefore that with one polarity of the left and right generator field winding LGmf and RGmf the compensating field windings LGcf and RGcf aid and oppose and with the opposite polarity of the left and right generator field windings oppose and aid.

With the strip for example coiled on the left coiler drum 18 and under conditions for rolling to the right through the rolls 14 and with the rolls 14 set to provide reduction in strip thickness, of for example 40%, the rolls operated by LCM

10

must run slower than the rolls operated by RCM because the same volume of strip must be taken from the rolls 14 during any interval of time as is fed to the rolls 14. Also, the coiler drum 18, due to the fact that the strip being fed therefrom is wound spirally thereon, must run at a progressively increasing speed if the strip is fed therefrom at a constant number of feet per minute, because of the constantly reducing diameter of the strip on the drum 18. Likewise, the speed of the drum 16 upon which the strip is being spirally wound must be continually decreased because of the increasing diameter of the spiral.

15

For purposes of explanation, assume a threading speed of 400 feet per minute of strip being fed from the work rolls 14 and a 40% reduction in strip thickness as it passes through the rolls 14. Since there is substantially no increase in strip width upon passing through the rolls 14, there is substantially a 40% increase in strip length which will require faster rotation of the motors RCM and RRM in the ratio of 1 to 1.66 neglecting for the instant the changing diameter of the coiler roll. In order to simplify this discussion, speeds of the various drums and rolls will be expressed in feet per minute of the periphery thereof, the periphery of the coiler drums 16 and 18 being assumed not to be

20

the actual periphery thereof the effective peripheral dimension at which the strip is being wound and which varies according to the amount of strip on the coiler drums. Further it is assumed that the ratio of coiler drum periphery to the periphery of the last turn of strip thereon at the end of the rolling operation is one to two. In some instances when convenient, the speeds of the various motors will be discussed and, when motor speeds are referred to, the speeds discussed will be the peripheral speeds at which the drums or rolls connected thereto are driven. For example, a speed of motor MM of 400 is the same as a speed of the rolls 14 of 400.

25

Now, therefore, under the assumed conditions, the various speeds at the start will be as follows: coiler drum 18, 120; left coiler roll 56 and left rolls 48 and 50, 240; work rolls 14, 400; right rolls 48 and 50 and right coiler roll 56, 400; and coiler drum 16, 400. The speeds of the rolls will remain constant for the operation but those of the drums 18 and 16 will change from 120 to 240 and from 400 to 200 respectively. When the strip is rolled in the opposite direction, the work rolls 14 remain at 400 but the drum 18 and left rolls 48 and 50 operate at the same speeds which the right rolls 48 and 50 operated at when rolling from left to right while the right rolls 48 and 50 operate at the same speeds as did the left rolls 48 and 50 in the left to right rolling. The normal speed of the drums 16 and 18 as determined by the potential of the right and left generators RG and LG due to excitation thereof by the fields RGmf and LGmf, respectively, with normal excitation on the motor fields RRMf and LRMf is 260. Therefore, if the compensating fields of the generators RGcf and LGcf are of a value to provide a 140 speed and are polarized to aid and oppose respectively the fields RGmf and LGmf, the drums 16 and 18 will rotate at speeds of 120 and 400 respectively, which speeds are those desired for left to right rolling. Therefore, upon initial rolling, the motors RRM and LRM operate at approximate correct speed.

30

The motors RCM and LCM are driven by the

35

right and left generators RG and LG respectively

40

and the motors RRM and LRM are driven by the

45

right and left generators RG and LG respectively

50

and the motors RCM and LCM are driven by the

55

right and left generators RG and LG respectively

60

and the motors RRM and LRM are driven by the

65

right and left generators RG and LG respectively

70

and the motors RCM and LCM are driven by the

75

right and left generators RG and LG respectively

in parallel with the motors RRM and LRM respectively. Assuming a normal starting speed of the motor LRM of 240 and necessarily with the same compensating effect for the winding $LGcf$ the normal speed with an uncompensated left generator LG would be 520. This figure is arrived at by the following method: normal speed of motor LRM (260) is to normal speed of motor LCM (unknown) as the compensated speed of motor LRM (120) is to the compensated speed of motor LCM (240). The result of this equation provides the 520 figure. The difference between 520 and 240 is 280 which is the compensating effect of the winding $LGcf$. Since the winding $RGcf$ aids the winding $RGmf$, the motor RCM will have a normal speed of 520 plus 280 or 800 which is greatly in excess of the desired speed. Resistors $FR4$ controlled by the relays CR and CL respectively, are, therefore, provided in the field circuit for the field windings $LCMf$ and $RCMf$. By arranging the resistor $FR4$ in the circuits for fields $LCMf$ and $RCMf$ and placing a shunt circuit around the resistors controlled by normally closed contacts CR8 and CL8 of the relays CR and CL and properly proportioning the value of the resistor $FR4$, the speeds of the motors LCM and RCM may be made 240 and 400 and 400 and 240, respectively, depending upon the rolling direction.

Since as above stated, the change in potential generated by the generator LG due to the effect of the winding $LGcf$ is too great, the normal speed of the motor LCM is lowered an amount such that, with the field $LCMf$ thereof energized in accordance with the potential of the generator LG, the low left to right rolling speed of the motor LCM is reduced below the desired speed and the high or right to left rolling speed is reduced to the desired speed. If now the resistance $FR4$ is placed in series circuit with the winding $LCMf$, the strength thereof for any given potential of the generator LG will be decreased causing an increase in speed of the motor LCM. The value of the resistor $FR4$ is, therefore, so chosen that when placed in series circuit with the field LCM, the strength of this field is reduced sufficiently to bring speed thereof up to the desired low speed of 240. Since the contacts CR3 are open for left to right rolling, the resistor $FR4$ will be in series circuit with the field $LCMf$ and the motor LCM will be rotating at desired speed. When the rolling is being done in a right to left direction, the contacts CR8 are closed and the resistor $FR4$ is effectively by-passed, whereby the energization of the field $LCMf$ is as if no resistor $FR4$ were added. Likewise, the resistor $FR4$ controlled by contacts CL8 of relay CL is associated with the motor RCM in the same manner.

Since the speed of rotation of the pilot exciter PE varies in accordance with the speed of the main motor MM, the potential generated thereby will also vary. Since the ratio between the excitation of the fields $LGcf$ and $RGcf$ with respect to the fields $LGmf$ and $RGmf$, respectively, must remain constant, the potential supplied to the fields $LGcf$ and $RGcf$ must vary in proportion to the potential of the exciter PE. Since the polarity of the fields $LGcf$ and $RGcf$ must remain fixed, they cannot be easily supplied by the exciter PE without complicated switching. A resistor $FR3$ has, therefore, been provided which is adjustable along with the resistor $FR2$ to provide for an increasing excitation of the fields $LGcf$ and $RGcf$ (decrease in value of resistance of $FR3$) with an increasing speed of the motor

MM (increase in value of resistance $FR2$) whereby the relative strengths of the fields $LGmf$ — $RGmf$ and $LGcf$ — $RGcf$ are maintained constant.

In Fig. 7, tension regulators $TR1$, $TR2$, $TR3$ and $TR4$ are shown connected for controlling the circuits of the motor fields $LCMf$, $RCMf$, $LRMf$ and $RRMf$, respectively. The terminals on the circuit diagram of the armature of the motor LCM indicated by the reference characters a^1 , a^2 , and a^3 are to be connected to correspondingly identified terminals of the regulator $TR1$. Similarly the terminals b^1 , b^2 , b^3 , c^1 , c^2 , c^3 , d^1 , d^2 and d^3 are to be connected to correspondingly identified terminals of the regulators $TR2$, $TR3$ and $TR4$.

The tension regulators $TR1$, $TR2$, $TR3$ and $TR4$ may be of any suitable type in which the motors controlled thereby are automatically controlled to transmit constant power to the load or to regenerate constant power from the load. One such arrangement is schematically shown in Fig. 12. The regulators $TR1$, $TR2$, $TR3$ and $TR4$ are identical. The regulator $TR1$, as shown in Fig. 12, comprises a pair of spaced series connected field coils 200 and 202 arranged to be connected in series with the armature circuit of the motor LCM and a rotatable coil 204 arranged between the coils 200 and 202 and connected in series circuit with a high value variable resistor $R1$ and across the armature terminals of motor LCM. The coil 204 will be rotated against the force of a suitable return spring, not shown, in proportion to the product of the forces exerted by the current flowing in the coils 200—202 and the coil 204. The current in coils 200 and 202 is proportional to the current through the armature of motor LCM while the current in coil 204 is proportional to the potential across the armature of motor LCM. Therefore, the coil 204 is rotated in accordance with the product of the motor volts and amperes and will assume a given position for a given power of the motor irrespective of the relative magnitudes of current and voltage.

The coil 204 carries an arm 206 having a contact which cooperates with a resistance element 208 whereby the energization of the field $LCMf$ may be regulated. Under motoring conditions of the motor LCM, the contacts CR8 will be closed and the resistor $FR4$ will be shunted out so that it has no effect on the energization of the coil $LCMf$. The resistance element 208 is positioned relative to the arm 206 so that when the desired power is being supplied to the motor LCM, the value of the resistance of the element 208 included in the circuit of the field $LCMf$ is that required for this operation of the motors at the desired power and the circuits are in balance. As the load on the motor increases, the arm 206 will be moved in a clockwise direction to decrease the value of the resistance in circuit with field $LCMf$. The resistance element 208 is positioned relative to the arm 206 so that when the motor LCM is operating for right to left rolling of the strip at just over the desired speed of 400 with no power delivered to or absorbed from the strip or in other words exerting no motoring or regenerative effect, the arm 206 is located substantially midway of the element 208, as shown in Fig. 11. The bias on the arm 206 is such that the power so required to drive the motor LCM as described and reflected by the coil 204 will hold the arm 206 in this substantially central position of the element 208 and the value of the resistance of element 208 in the circuit of the field $LCMf$ is

that required to permit the correct degree of energization of this field. Since the motor LCM cannot operate under these conditions because the strip speed is only 400, the motor will run at 400 and deliver power to the strip. This increase in delivered power of the motor LCM is reflected by an increase in power supplied thereto by the generator LG and by a movement of the arm 206 in a clockwise direction under influence of the rotatable coil 204, whereby the value of the resistance 208 included in the circuit of field LCMf is decreased to increase the excitation of the field LCMf. The change in resistance so afforded is just sufficient to decrease the normal no-load motor speed an amount such that the motor LCM will operate at the 400 speed and deliver the desired predetermined amount of power to the strip.

If now for some reason or other the power absorbed by the motor LCM from the generator LG tends to increase, the arm 206 under the influence of the coil 204 will move clockwise thereby decreasing the value of the resistance of the element 208 in the circuit of field LCMf increasing the field strength thereof and tending to make the motor operate at a lower speed but with the same power output. Since motor LCM is designed to operate at a constant speed because the strip is passing over the rollers driven thereby at fixed speed, the use of the regulator TR1 is precautionary only and should seldom, except in cases of disruption of normal operation, be called into play.

The regulator TR3, however, has an important function. The normal speed of the motor LRM which drives the drum 18 is adjusted by its regulator TR3, with the contacts CL3a open and thereby rendering the resistor FR5 effective, to a speed just above the initial desired operating speed. With the strip being wound directly on its peripheral surface, it must operate at the 400 speed and the regulator TR3 will adjust the strength of its field LRMf so that when operating at the 400 speed it will deliver the desired power to the strip, as described in connection with regulator TR1 and motor LCM. As the strip is wound about the drum 18, the effective drum diameter at the point of winding is increased and the speed of the drum 18 must be reduced since the strip will tend to be wound on the drum 18 faster than it is delivered by the rolls 14. If the motor speed were not reduced, the strip would be torn apart. However, as the effective winding diameter of drum 18 increases and the strip tends to wind on the drum 18 faster than it is delivered by the rolls 14, the power required to drive the motor LRM will increase. This increase in power is immediately reflected by the coil 204 which rotates the arm 206 clockwise to decrease the value of the resistance of element 208 in the circuit of the field LRMf increasing the strength of the field LRMf and decreasing the speed of the motor LRM. The relationship of the movement of the arm 206 by the coil 204 relative to the element 208 provides for an increased excitation of the field LRMf in correct proportion to reduce the speed of the motor LRM whereby constant power is delivered thereby to the drum 18. Therefore, since the power delivered by the motors LCM and LRM is held constant and the strip speed is constant, the tension of the strip leaving the rolls 14 will be constant.

Referring to the motor LRM and assuming the strip is moving from left to right, the motor LRM will act to apply a resisting pull or tension

on the strip as it enters the rolls 14 and they, therefore, will be regenerating power into the generator LG which will be of a constant magnitude since the tension of, and speed of, movement of the strip into the rolls 14 is to be held constant. Under such conditions, the relay contacts CL8a will be closed due to the de-energization of relay CL and the value of the resistor FR5 associated with the fields LRMf will be subtracted from the resistance of the portion of the element 208 in circuit with the field LRMf to increase the strength thereof.

The value of the resistor FR5 is chosen so that when its value is subtracted from the value of the resistance of the element 208 and the arm 206 is at the substantially midway setting, the excitation of the field LRMf is such that at no-load the motor LRM will operate at a speed slightly less than 120 which, as stated hereinbefore, is the initial desired speed for the drum 18 when unwinding. It should be here noted that as far as the operation of the regulator is concerned this is equivalent to the 400 speed because the reduction from 400 to 120 is accomplished by the effect of the field LGcf. The value of the resistor FR5 is, therefore, only of sufficient value so that its absence lowers the no-load speed of the motor LRM only a few revolutions per minute.

Under these conditions the motor will attempt to operate just slower than the speed of the strip leaves the drum 18 when the strip is substantially fully wound thereon. Since the strip will leave the drum 18 at the desired speed or 120, the motor LRM will be turned faster than the setting of the field LRMf is set to operate the motor LRM and, therefore, the motor will regenerate power. This regenerated power will cause the coil 204 to rotate the arm 206 counterclockwise increasing the value of the resistance of element 208 in the circuit of the field LRMf decreasing the energization thereof and therefore the power regenerated. The relationship of this portion of the element 208 to the position of the arm 206 as determined by the coil 204 is such that a substantially constant predetermined amount of power is regenerated thereby putting a constant drag or tension on the strip being rolled.

As the speed of the drum 18 increases because of the lesser diameter of the strip being unwound therefrom, the speed of the motor LRM will increase. This increase in speed tends to cause more power to be regenerated thereby, but as the power increases, the coil 204 moves the arm 206 further in a counterclockwise direction still further reducing the strength of field LRMf and maintaining its power output constant with a constant tension on the strip being unwound from the drum 18.

Referring to the regulator TR1, and the resistor FR4 associated therewith, as explained hereinbefore the normal strength of the field LCMf is adjusted to operate the motor LCM at the 400 speed which is used when the strip is being rolled from right to left and being wound on drum 18. When rolling from left to right under the same relative field excitation due to the action of the field LGcf on the generator LG, the speed of motor LCM would be too slow and, therefore, the resistance FR4 was inserted to bring the speed up to that desired. Without the use of the regulator TR1, this would correctly describe the function and co-operation of the resistor FR4, however, as has just been seen in

connection with the functioning of the regulator TR3, a given resistance must be subtracted from the regulator element 203 at the midway setting of the arm 206 when the strip being rolled is moving right to left. Normally the magnitude of the resistance to be subtracted to adjust the regulator TR1 is less than the value of the resistance which must be added to compensate for the effect of the lowered voltage of the generator LG, due to the field LGcf. Therefore, the magnitude of the resistor FR4 as originally defined should be reduced by the value necessary to recalibrate the regulator TR1. Since the magnitude of the increased resistance to overcome the lowered voltage of generator LG is greater than the magnitude of the recalibrating resistance, the shunt circuit therefor is still actuated by normally closed contacts of the relay CR. If the opposite were true, the shunt circuit would be controlled by normally closed contacts of the relay CL the same as control the resistor FR5.

The motors RCM and RRM are controlled by the regulators TR2 and TR4 in the same manner as motors LCM and LRM are controlled by the regulators TR1 and TR3. The resistors FR4 and FR5 with regulators TR2 and TR4 and shunted by normally closed contacts CL8 and CR3a, respectively, co-operate to produce the same effect as described with the resistors FR4 and FR5 associated with the regulators TR1 and TR3. Since the regulators TR1, TR2, TR3, and TR4 act in accordance with power either supplied to or regenerated by the motors LCM, RCM, LRM and RRM to maintain tension on the strip being rolled, the voltage supplied by the generators LG and RG or the speed of rolling (threading to rolling) is immaterial to the tension maintained.

The strip, therefore, will roll either left to right or right to left under predetermined desired tension, the guides 30 and 32 will alternately guide the strip as it enters the rolls 14, and the heat lost to the strip during rolling will be replaced by the furnaces. This rolling will be done at a high speed in which the strip moves rapidly through the mill 1 and threaded to the drums 16 and 18 at a relatively low speed.

I claim as my invention:

1. A coiler assembly adapted to use with reversing hot strip mills comprising a coiler furnace, a coiler drum rotatable in said furnace, said coiler drum having a peripheral surface about which a strip may be wound and a strip-receiving aperture through the said peripheral surface, an electric motor connected to rotate said drum, electric control means arranged to act on said motor to bring the aperture of the said drum into strip-receiving position and to hold the drum so positioned, rolls cooperative with the said coiler drum to feed the strip to the drum, a motor for rotating the said cooperative rolls, and electric control means actuated by a strip approaching the said furnace and operating with time delay to energize the said drum-rotating motor and to energize the motor for rotating the rolls cooperative with the coiler drum.

2. A coiler assembly adapted to use with reversing hot strip mills comprising a coiler furnace, a coiler drum rotatable in said furnace, said coiler drum having a peripheral surface about which a strip may be wound and a strip-receiving aperture through the said peripheral surface, an electric motor connected to rotate said drum, electric control means arranged to act on said motor to bring the aperture of the said

drum into strip-receiving position and to hold the drum so positioned, rolls cooperative with the said coiler drum to feed the strip to the drum, a motor for rotating the said cooperative rolls, electric control means actuated by a strip approaching the said furnace and operating with time delay to energize the said drum-rotating motor and to energize the motor for rotating the rolls cooperative with the coiler drum, and electric control means arranged so to act on the said drum-rotating motor as to reverse the direction of rotation of the drum to pay out the strip wound thereon.

3. A coiler assembly adapted to use with reversing hot strip mills comprising a coiler furnace, a coiler drum rotatable in said furnace, said coiler drum having a peripheral surface about which a strip may be wound and a strip-receiving aperture through the said peripheral surface, an electric motor connected to rotate said drum, electric control means arranged to act on said motor to bring the aperture of the said drum into strip-receiving position and to hold the drum so positioned, a coiler roll adapted to contact the said coiler drum to hold the strip initially to the drum, roll-positioning means for advancing and retracting the said coiler roll into and out of cooperative relation with said drum, electric control means arranged to actuate the said roll-positioning means to advance the coiler roll into contact with the drum, electric control means actuated by a strip approaching the said furnace and operating with time delay to energize the said drum-rotating motor to wind the strip on the drums, and electric control means acting under the influence of the said strip arranged to actuate the said roll-positioning means to retract the said coiler roll when winding of the strip on the drum has begun in manner to secure the strip thereon.

4. A coiler assembly adapted to use with reversing hot strip mills comprising a coiler furnace, a coiler drum rotatable in said furnace, said coiler drum having a peripheral surface about which a strip may be wound and a strip-receiving aperture through the said peripheral surface, an electric motor operatively connected to said coiler drum to rotate the drum, an electric drum-positioning control assembly comprising electric control means effective to energize the drum-rotating motor and electric control means comprising a limit switch responsive to the position of the said coiler drum effective to terminate rotation of the drum with the peripheral aperture thereof in strip-receiving position, a coiler roll adapted to contact the said coiler drum to hold the strip initially to the drum, roll-positioning means for advancing and retracting the said coiler roll into and out of cooperative relation with said drum, and electric control means arranged to actuate the said roll-positioning means to advance the coiler roll into contact with the drum.

5. A coiler assembly adapted to use with reversing hot strip mills comprising a coiler furnace, a coiler drum rotatable in said furnace, said coiler drum having a peripheral surface about which a strip may be wound and a strip-receiving aperture through the said peripheral surface, an electric motor operatively connected to said coiler drum to rotate the drum, an electric drum-positioning control assembly comprising electric control means effective to energize the drum-rotating motor and electric control means comprising a limit switch responsive to the position

of the said coiler drum effective to terminate rotation of the drum with the peripheral aperture thereof in strip-receiving position, additional electric control means actuated by a strip approaching the said furnace operative with time delay to energize the said drum-rotating motor and cause strip-winding rotation of the drum, a coiler roll adapted to contact the said coiler drum to hold the strip initially to the drum, roll-positioning means for advancing and retracting the said coiler roll into and out of cooperative relation with said drum, electric control means arranged to actuate the said roll-positioning means to advance the coiler roll into contact with the drum, and electric control means acting under the influence of the said strip arranged to actuate the said roll-positioning means to retract the said coiler roll when winding of the strip on the drum has begun in manner to secure the strip thereon.

6. A coiler assembly adapted to use with reversing hot strip mills comprising a coiler furnace, a coiler drum rotatable in said furnace, said coiler drum having a peripheral surface about which a strip may be wound and a strip-receiving aperture through the said peripheral surface, an electric motor operatively connected to said coiler drum to rotate the drum, an electric drum positioning control assembly comprising electric control means effective to energize the drum-rotating motor and electric control means comprising a limit switch responsive to the position of the said coiler drum effective to terminate rotation of the drum with the peripheral aperture thereof in strip-receiving position, additional electric control means actuated by a strip approaching the said furnace operative with time delay to energize the said drum-rotating motor and cause strip-winding rotation of the drum, a coiler roll adapted to contact the said coiler drum to hold the strip initially to the drum, roll-positioning means for advancing and retracting the said coiler roll into and out of cooperative relation with said drum, electric control means arranged to actuate the said roll-positioning means to advance the coiler roll into contact with the drum, electric control means acting under the influence of the said strip arranged to actuate the said roll-positioning means to retract the said coiler roll when winding of the strip on the drum has begun in manner to secure the strip thereon, and electric control means arranged so to act on the said drum-rotating motor as to reverse the direction of rotation of the drum to pay out the strip wound thereon.

7. A strip-handling installation composed of two cooperative coiler assemblies adapted to wind

a metal strip back and forth therebetween for the performance of work thereon, each said coiler assembly comprising a coiler furnace, a coiler drum having a peripheral surface about which a strip may be wound and a strip-receiving aperture through the said peripheral surface, an electric motor connected to rotate said drum, rolls cooperative with the said coiler drum to feed a strip to the drum, a motor for rotating the said cooperative rolls, electric control means associated with the drum-rotating motor of each coiler assembly, a strip-operated switch associated with the electric control means of each said motor, the said strip-operated switch of each said assembly being arranged so to act on the electric control means of the other said assembly as to cause positioning rotation of the coiler drum of the said other assembly into strip-receiving position and to cause rotation of the said cooperative rolls, and a limit switch associated with each said coiler drum effective to stop the drum in position to receive the approaching end of the strip.

8. A strip-handling installation composed of two cooperative coiler assemblies adapted to wind a metal strip back and forth therebetween for the performance of work thereon, each said coiler assembly comprising a coiler furnace, a coiler drum having a peripheral surface about which a strip may be wound and a strip-receiving aperture through the said peripheral surface, an electric motor connected to rotate said drums, electric control means associated with the drum-rotating motor of each coiler assembly, a strip-operated switch associated with the electric control means of each said motor, the said strip-operated switch of each assembly being arranged so to act on the electric control of the other said assembly as to cause positioning rotation of the said other assembly into strip-receiving position, a limit switch associated with each said coiler drum effective to stop positioning rotation with the drum in position to receive the approaching end of the strip, and the said strip-operated switch associated in each assembly being effective with time delay to cause strip winding rotation of the associated coiler drum under the influence of the end of a strip approaching the furnace of that assembly.
